UNITED STATES PATENT OFFICE

136,861

DESIGN FOR A DEVICE FOR CENTERING SHAFTS, DRILLS, OR THE LIKE

Crawford L. Wilson, Beckley, W. Va.

Application January 22, 1943, Serial No. 109,324

Term of patent 14 years

To all whom it may concern:

Be it known that I, Crawford L. Wilson, a citizen of the United States, residing at Beckley, county of Raleigh, and State of West Virginia, have invented a new, original, and ornamental Design for a Device for Centering Shafts, Drills, or the like, of which the following is a specification, reference being had therein to the accompanying drawing forming part thereof.

In the drawing:

Fig. 1 is an edge elevational view of a device for centering shafts, drills, or the like, showing my new design;

Fig. 2 is a side elevational view thereof with the front cup member illustrated in vertical section; and

Fig. 3 is a fragmentary rear end view thereof with the handles broken away for convenience of illustration.

I claim:

The ornamental design for a device for centering shafts, drills, or the like, as shown.

CRAWFORD L. WILSON.
